UNITED STATES PATENT OFFICE

ALVIN F. NYE, OF ROCHESTER, NEW YORK

ROLLER SCREEN MOUNTING

Application filed July 22, 1929. Serial No. 380,014.

My present invention relates to roller screen mountings of such a type as is used to supply windows with fly screens as permanent fixtures, the screen being drawn down when in use in the manner of a window shade and at other times rolled up upon a spring roller and the invention has for its object to provide a simple, cheap and serviceable mounting of this kind having certain advantages in construction and mode of operation. The improvements are directed in part toward providing a certain elasticity in the assembly of the parts whereby the fixture need not be cut with extreme exactness in order to fit the window casing and further toward providing simple and accessible means for varying the tension of the roller spring.

To these and other ends the invention resides in certain improvements and combinations of parts, all as will be hereinafter more fully described, the novel features being pointed out in the claims at the end of the specification.

In the drawings:

Fig. 1 is an elevation, broken away at the center, of a window casing fitted with a roller screen mounting constructed in accordance with and illustrating one embodiment of my invention;

Fig. 2 is an enlarged central longitudinal section through the roller and casing shown in Fig. 1 broken away at the center;

Fig. 3 is a further enlarged section taken on the line 3-3 of Fig. 2;

Fig. 4 is an inside elevation of the adjusting bracket shown at the right in Fig. 2 as it appears removed from the remainder of the structure;

Fig. 5 is a section, partly broken away, taken on the line 5-5 of Fig. 3;

Fig. 6 is an enlarged section taken on the line 6-6 of Fig. 2 looking in the direction of the arrow;

Fig. 7 is a section taken on the line 7-7 of Fig. 2 looking in the direction of the arrows;

Fig. 8 is a section taken on the line 8-8 of Fig. 2 looking in the direction of the arrows;

Fig. 9 is an enlarged section taken on the line 9-9 of Fig. 2;

Fig. 10 is an end elevation of the adjusting bracket, being a view from the other side of this part as shown in Fig. 4;

Fig. 11 is an enlarged section through the adjusting bracket taken substantially on the line 11-11 of Fig. 4;

Fig. 12 is a rear view of the spring tensioning bracket shown in Fig. 10;

Fig. 13 is a top view thereof;

Fig. 14 is an enlarged fragmentary section taken on the line 14-14 of Fig. 13; and

Fig. 15 is an end elevation of the worm gear shown in Fig. 11 detached.

Similar reference numerals throughout the several views indicate the same parts.

This application is a continuation in part of my prior pending application Serial No. 180,122, filed April 1, 1927, in which is shown to a large extent a window screen fitting of the general nature here involved, but claiming principally the means for extending the screen from the roller support over the window opening and securing it in place while, as above stated, this case is more intimately concerned with the construction and mode of operation of the screen roller itself. As in my former case referred to, I have also shown in this case, but in a general way, (Fig. 1) a window casing A having a sill B. A screen roll casing indicated generally at C is supported at the top of the window frame in brackets D and E. The screen itself is indicated at F and terminates in a bottom rail G. In the general showing of Fig. 1 the screen is shown extended in operative position to cover the window opening of the frame, namely, it is drawn down from the roller hereinafter described so that the bottom rail G thereof is secured against the window sill B by means not necessary to show herein.

It may be stated here that, in the present showing, the bracket E is the one which is fitted with the mechanism for increasing or diminishing the tension of the spring that winds the screen roller, all as hereinafter described. Inasmuch as the two brackets D and E are constructed alike in some respects, a

description of one will suffice for both up to a certain point.

Each comprises a back plate 1 having a rearwardly offset attaching portion 2 at its lower end provided with screw holes 3. The back plate 1 constitutes in reality an inturned flange on an end plate 4 provided with a downwardly extending attaching portion 5 also provided with screw holes 6 and of which the aforesaid attaching portion 2 constitutes an inturned flange, the idea obviously being to form a corner bracket fitting the corner of the window casing. The general shape of the bracket is semi-circular or semi-cylindrical and the edges of the end plate 4 in continuation forwardly of the back plate 1 are also turned inwardly to constitute a spacing flange 7. A strap 8 encircles this flange on the outside and a similar strap or band 9 on the inside, which two straps are held in place by bent over ears 10 that are extended through openings in the spacing flange and the other strap as shown in Fig. 14, said ears being preferably formed integrally with one, the inner, strap.

The two straps 8 and 9 thus spaced from a socket of substantial depth for a similarly shaped sheet metal casing element previously indicated at C, the ends of which telescopically fit these sockets as best shown in Fig. 2. The idea in general is that if a number of screen mountings are cut to the same length to fit windows of generally the same size and yet the window frames vary a little in their individual widths, then, in that case, the slidability of the casing C in the end brackets will make up for the difference. The exterior appearance will be the same on all of the windows, and the engagement of the casing with the brackets will be secure even though the casing does not in each instance extend the full depth thereof.

Secured to the end plate 4 of each bracket is an inwardly projecting tubular hub 11, the ends of which may be fastened thereto by bent over ears 12 formed thereon and extending through the plates. These hubs are of substantial length, that is, they should preferably be longer than the width of the socket forming strap 8 and 9. The tubular core 13 of the screen roller is mounted on these hubs into which the latter projects and here again the element of extensibility is introduced so that if the said core is cut relatively short as compared with the separation of the brackets D and E due to a slightly greater width of the window casing it will adjust itself telescopically on the hub supports 11 and still be adequately supported.

The screen roller itself embodying this central core piece 13 comprises also an outer winding shell 14 surrounding the core and supported in spaced relationship thereto to form a chamber 15, in which latter is housed the spiral tensioning spring 16 that surrounds

the core, as shown, and winds the roll. The shell 14 is so supported on the core by means of a pair of collars 17 and 18, which turn freely on the core but which are on the other hand, locked to the sleeve or roller shell 14. The mode of locking them is preferably as follows:

The collars 17 and 18 are preferably composed of annular castings having a plurality of indentations 19 in their peripheries at separated points. With a suitable die, I punch portions of the shell into these indentations 19 as shown at 20 in Fig. 5, so that the shell is thereby locked to the collars against both relative, rotative and endwise movements, which arrangement, in view of the showing of Fig. 5, is thought to require no further description.

The seam of the tubular shell 14 is shown generally at 21 in Fig. 3. The overlapped portions thereof are accommodated in a further wider depression 22 in the collars 17 and 18 and suitably secured together, as by soldering, while at the same time securing between them the inside edge of the screen F, as also clearly shown in Fig. 3, and also in Figs. 7 and 8. As further shown in these same figures, the screen passes from this point of attachment on the roller shell out through an opening 23 at the rear and bottom of casing C and adjacent to back plate 1, as shown in Figs. 7 and 8.

This opening 23 is provided for in the mode of attaching casing C to the bracket supports D and E through the provision of the sockets in the latter, aforesaid, in the following manner:

The casing C embodies a backing or base plate 24 to which it is attached at the top (Figs. 7 and 8) by interlocking flanges indicated generally at 25. At the bottom, it is doubled back or flanged at 26 so that this edge interlocks with the outer strap 8 of each bracket as the casing is slid lengthwise into engagement with the latter. At the same time, the base plate 24 engages in the rear of the portions 1 of the bracket, its lower edge being engaged under a finger 26a on the attaching portion 2 thereof. It is for this reason that the attaching portion 2 is offset from the bracket portion 1 and when the parts are assembled, as just described, a substantially flat or continuous surface is presented at the rear to go against the window casing.

Returning to a further description of the screen roll itself, it is to be borne in mind that the spacing and supporting collars 17 and 18 between the core 13 and the shell 14 are fixed to the latter, as shown in Fig. 5, but are free on the core, or, rather, the core is free to turn relatively to these collars and to the shell. One end of the spring 16 is engaged with the core 13, as indicated at 27 in Figs. 2 and 6, by being secured to the eye of a cotter pin 28 extending through the latter.

The other end 29 is anchored in the opposite collar 18, as shown in Figs. 2 and 8.

The core does not turn but remains fixed during operation of drawing the screen down from the roller shell 14 which latter then rotates freely on the core. The screen is returned by the spring 16 rotating the shell 14 in the reverse direction in the ordinary manner, the spring reacting between the core and shell. As aforesaid, I provide means for regulating the tension of the spring, which means is constituted in the present instance as follows:

The core 13 is held against rotation during the beforementioned movements by reason of channels 30 on one end thereof that interlock with ribs 31 on a sleeve 32 that itself turns on hub 11. However, sleeve 32 is fixed to a worm gear 33 supported in bearing bracket 34 attached to the inner side of end wall 4 of bracket E. Meshing with this worm gear is a worm 35 (Figs. 4 and 11) also having bearings in bracket 34 and having a shaft or stem 36 extending downwardly through and to the exterior of the said bracket and the general casing or housing of the mechanism. This stem is shown channelled at 37 in the manner of a screw head so that it may be rotated with a suitable tool. It will be understood from this without further explanation that turning the worm slowly rotates the worm gear which, through its sleeve 32, rotates the core and hence changes the tension of the spring to store greater or less power therein as desired according to the direction of the turning movement.

A device constructed in accordance with my invention as herein described and shown has few parts which are easily assembled and can be readily applied to its position on the window frame once the casing C, shell 14 and core 13 are cut to approximately the proper length. It is further pointed out that the interlocking for rotation of the worm gear sleeve with the core does not interfere with the longitudinal sliding adjustment of the core thereon and hence, indirectly, on the hub 11.

I claim as my invention:

1. In a roller screen mounting, the combination with end brackets having inwardly projecting hubs thereon, of a tubular core piece slidable telescopically on the hubs, a screen roller shell enclosing the core piece and supported thereon for relative movement and forming a chamber, and a spring in the chamber reacting between the core piece and shell.

2. In a roller screen mounting, the combination with end brackets having inwardly projecting hubs thereon, of a tubular core piece slidable telescopically on the hubs, a screen roller shell enclosing the core piece and supported thereon for relative movement and forming a chamber, a spring in the cham-

ber reacting between the core piece and shell, and means for regulating the tension of the spring.

3. In a roller screen mounting, the combination with end brackets having inwardly projecting hubs thereon, of a tubular core piece slidable telescopically on the hubs, a screen roller shell enclosing the core piece and supported thereon for relative movement and forming a chamber, a spring in the chamber reacting between the core piece and shell, a sleeve mounted on one of the hubs, and means acting through the sleeve for regulating the tension of the spring.

4. In a roller screen mounting, the combination with end brackets having inwardly projecting hubs thereon, a sleeve mounted on one of the hubs, of a tubular core piece slidable telescopically on the sleeve but locked for rotation with the sleeve, a screen roller shell enclosing the core piece and supported thereon for relative movement and forming a chamber, a spring in the chamber reacting between the core piece and shell, and means for adjusting the sleeve which is locked for rotation with the core piece in a plurality of rotative positions.

5. In a roller screen mounting, the combination with end supports, a core piece mounted on the end supports, a screen roller shell rotatively mounted on the core piece and forming a chamber therewith, a spring in the chamber reacting between the core piece and shell and means for rotating the core piece to different fixed positions relatively to the end supports to vary the normal tension of the spring as exerted against the shell, said means comprising worm gearing mounted on one of the end supports and having operating mechanism accessible exteriorly thereof.

6. In a roller screen mounting, the combination with end brackets having inwardly projecting hubs thereon, of a tubular core piece slidable telescopically on the hubs but locked for rotation with one of them, a screen roller shell enclosing the core piece and supported thereon for relative movement and forming a chamber, a spring in the chamber reacting between the core piece and shell, and means for adjusting the hub which is locked for rotation with the core piece in a plurality of rotative positions, comprising a worm gear on the hub and a worm supported in the adjacent bracket and having an operating portion accessible exteriorly of the bracket.

7. In a roller screen, the combination with a roll embodying a core and an outer shell, of end brackets having end supports for the roll projecting into the shell and onto which the core ends project and are secured.

ALVIN F. NYE.
